[57] **ABSTRACT**

A series of novel substituted hexahydro imidazoquinoline compounds have been prepared from the corresponding 2-aminomethyl-1,2,3,4-tetrahydroisoquinolines. These compounds are useful in the field of chemotherapy as anti-schistosomal agents. Preferred members include 2-(lower alkyl)-7-methyl-8-nitro-1,2,3,3a,4,5-hexahydroimidazo-[1,5-a]quinolines, 2-(lower alkyl)-7-hydroxymethyl-8-nitro-1,2,3,3a,4,5-hexahydroimidazo-[1,5-a]quinolines and 2-(lower alkyl)-7-methyl-8-chloro-1,2,3,3a,4,5-hexahydroimidazo-[1,5-a]quinolines, as well as various 1- and 9-substituted derivatives thereof.

10 Claims, No Drawings

HEXAHYDRO IMIDAZOQUINOLINES

BACKGROUND OF THE INVENTION

This invention relates to certain new and useful hexahydro imidazoquinoline compounds of principal interest to those in the field of chemotherapy. More particularly, it is concerned with various novel substituted hexahydro imidazoquinolines and their non-toxic acid addition salts, which are of especial value in view of their anti-schistosomal properties.

In the past, various attempts have been made by numerous investigators in this particular field of therapy to obtain new and still better forms of agents and/or methods for the treatment of schistosomiasis. In many instances, these efforts have further involved the synthesis and testing of various new organic compounds, particularly in the category of nitrogen heterocycles. For instance, in British Pat. No. 837,306, there is disclosed a series of dicarboxylic acid monopiperazines with a 3-halogen-4-methylphenyl moiety located at the 1-position of the piperazine ring that are reported as being active against schistosomiasis. However, little is known about the effect of other di-nitrogen ring heterocycles in this area and the existing therapy, unfortunately, still suffers from a number of known drawbacks, such as, e.g., relatively low potency (requiring more than a single dose of therapy), problems of toxicity, the lack of a demonstrated prophylactic effect, etc.

SUMMARY OF THE INVENTION

In accordance with the present invention, it has now been surprisingly found that certain novel substituted hexahydro imidazoquinoline compounds are extremely useful when employed in the field of drug therapy as anti-schistosomal agents. The novel compounds of this invention are all selected from the group consisting of substituted 1,2,3,3a,4,5-hexahydroimidazo-[1,5-a]-quinoline bases of the formula:

and the N-oxide derivatives and pharmaceutically acceptable acid addition salts thereof, wherein R₁ is a member selected from the group consisting of alkyl having from one to six carbon atoms, hydroxylalkyl having from two to six carbon atoms, alkoxyalkyl having from two to six carbon atoms in the oxyalkyl moiety and from one to six carbon atoms in the alkyl moiety, alkanoyloxyalkyl having from two to six carbon atoms in the oxyalkyl moiety and from two to six carbon atoms in the alkanoyl moiety, cycloalkyl having from three to six carbon atoms and phenylalkyl having up to three carbon atoms in the alkyl moiety; R₂ is a member selected from the group consisting of methyl, formyl, hydroxymethyl, alkoxyethyl having from one to six carbon atoms in the alkyl moiety and alkanoyloxyethyl having from two to six carbon atoms in the alkanoyl moiety; R₃ is a member selected from the group consisting of nitro, cyano, fluorine, chlorine and bromine; R₄ and R₅ are each a member selected from the group consisting of hydrogen and alkyl having from one to six carbon atoms, and R₆ is a member selected from the group consisting of hydrogen, alkyl having from one to six carbon atoms, phenylalkyl having up to three carbon atoms in the alkyl moiety, phenyl, nitrophenyl, naphthyl, furyl, thiophenyl and pyridyl. These compounds all possess anti-schistosomal activity and are therefore, useful in the treatment of schistosomiasis and/or for the control of schistosome infections.

Of especial interest in this connection are the preferred compounds of the present invention where R₁ in the aforesaid structural formula is alkyl having from two to four carbon

atoms (and most preferably, a branched-chain alkyl having 3-4 carbon atoms, e.g., isopropyl), R₂ is methyl, hydroxymethyl, or ethoxymethyl, R₃ is nitro or chloro, R₄ is hydrogen, R₅ is hydrogen or methyl, and R₆ is hydrogen, 5 methyl, ethyl, phenyl, nitrophenyl or thiophenyl. Typical member compounds of the preferred class include such 2-(lower alkyl)-7-methyl (or hydroxymethyl)-8-nitro (or chloro)-1,2,3,3a,4,5-hexahydroimidazo-[1,5-a]-quinolines as 2-isopropyl-7-methyl-8-nitro-1,2,3,3a,4,5-hexahydroimidazo-[1,5-a]-quinoline, 1,7-dimethyl-2-isopropyl-8-nitro-1,2,3,3a,4,5-hexahydroimidazo-[1,5-a]-quinoline, 2-isopropyl-7-hydroxymethyl-8-nitro-1,2,3,3a,4,5-hexahydroimidazo-[1,5-a]-quinoline, 1-ethyl-2-isopropyl-7-methyl-8-nitro-1,2,3,3a,4,5-hexahydroimidazo-[1,5-a]-quinoline, 1-phenyl-2-isopropyl-7-methyl-8-nitro-1,2,3,3a,4,5-hexahydroimidazo-[1,5-a]-quinoline, 2-isopropyl-7,9-dimethyl-8-chloro-1,2,3,3a,4,5-hexahydroimidazo-[1,5-a]-quinoline, 1,2,7-trimethyl-8-nitro-1,2,3,3a,4,5-hexahydroimidazo-[1,5-a]-quinoline, 1-(2-thienyl)-2-isopropyl-7-methyl-8-nitro-1,2,3,3a,4,5-hexahydroimidazo-[1,5-a]-quinoline, 1-(2-nitrophenyl)-2-isopropyl-7-methyl-8-nitro-1,2,3,3a,4,5-hexahydroimidazo-[1,5-a]-quinoline and 1-methyl-2-isopropyl-7-ethoxymethyl-8-nitro-1,2,3,3a,4,5-hexahydroimidazo-[1,5-a]-quinoline, respectively. These particular compounds are all highly potent as regards anti-schistosomal activity.

DETAILED DESCRIPTION OF THE INVENTION

30 In accordance with the process employed for preparing the novel compounds of this invention, an appropriately substituted 2-aminomethyl-1,2,3,4-tetrahydroquinoline (see British Pat. No. 1,166,538) is treated with an aldehyde of the formula R₆-CHO, where R₆ is defined as aforesaid. This particular reaction is normally carried out in the presence of a suitable solvent for the aldehyde, e.g., water or ethanol, or it may be carried out in the absence of a solvent by merely suspending the tetrahydroquinoline compound in the liquid aldehyde. In general, the reaction is conducted at a temperature that is in the range of from about 0° C. to about 100° C. for a period of about 15 minutes to about four hours.

The N-oxide derivatives of the compounds of this invention, i.e., N-oxide derivatives of the aforementioned novel substituted hexahydro imidazoquinolines, may be prepared by simply using well-known synthetic methods to effect such a conversion from the parent compound, e.g., oxidation via 30 percent hydrogen peroxide or benzoyl peroxide, etc. The esters of those compounds containing free hydroxyl groups are also prepared by conventional means.

Inasmuch as the substituted hexahydro imidazoquinoline compounds of this invention all possess asymmetric carbon atoms at positions 1 and 3a of the imidazoquinoline fused ring system, they may exist in separated d- and l-optically active forms, as well as in racemic dl-mixtures necessarily produced by the present synthetic methods as hereinbefore described. The invention contemplates the d-, l- and racemic forms within its scope.

60 The acids which are used to prepare the pharmaceutically acceptable acid addition salts of the aforementioned hexahydro imidazoquinoline base compounds of this invention are those which form non-toxic acid addition salts, i.e., salts containing pharmacologically acceptable anions, such as the hydrochloride, hydrobromide, hydroiodide, sulfate or bisulfate, phosphate or acid phosphate, acetate, maleate, fumarate, lactate, tartrate, citrate, gluconate, saccharate, methanesulfonate, p-toluenesulfonate and pamoate (i.e., 1,1-methylene-bis-2-hydroxy-3-naphthoate) salts.

65 70 The compounds of the invention can be administered alone, but will generally be administered in conjunction with a pharmaceutical carrier. The carrier is normally selected with regard to the intended route of administration, as well as standard pharmaceutical practice. For example, these compounds may be administered orally in the form of tablets containing

excipients such as starch or milk sugar (lactose), or in capsules either alone or on admixture with excipients, or else in the form of elixirs or suspensions containing flavoring or coloring agents, etc. For purposes of parenteral administration, they are best used in the form of a sterile aqueous solution of a water-soluble salt (e.g., the methanesulfonate salt), which solution may also contain sufficient saline or glucose to render the final composition isotonic.

The activity of the compounds of the present invention, as schistosomicides, has been determined by a technique which depends on the movement of adult schistosomes from their normal sites in the mesenteric veins to the veins within the liver, as effected by chemotherapeutically-active compounds. This technique has been described in detail in the *Journal of Tropical Medicine & Hygiene*, Vol. 71, pp. 139-145 (June, 1968). In the present case, white mice of 3-4 weeks age were infected percutaneously with 120 cercariae of *Schistosoma mansoni* (East African strain). Eight weeks after infection, the compound to be assessed was administered orally or intraperitoneally at a basic dosage of 25 mg./kg. daily for a period of 4 days, or at 50 mg./kg. in a single dose. Efficacy was then assessed 24 hours after the last dose of multiple dosage, or 72 hours after a single dose. Mice were perfused post mortem to recover the worms separately from the mesenteric veins, as well as from the hepatic portal vein and from the veins within the liver. The proportional movement of worms from the portal and mesenteric veins to the veins within the liver formed the basis for the assessment.

EXAMPLE I

A suspension of 2-isopropylaminomethyl-6-methyl-7-nitro-1,2,3,4-tetrahydroquinoline (1.5 g.) in formalin (10 ml.) was mechanically shaken for a period of two hours, after which time a dark-red solid precipitated. The reaction mixture was then treated with water containing 5N sodium hydroxide solution (20 ml.) and extracted with diethyl ether (2 x 75 ml.). The ethereal solution was dried over anhydrous magnesium sulfate and evaporated in vacuo to yield a viscous blood-red oil, which crystallized on standing. The latter material was subsequently dissolved in hot petroleum ether (b.p. 60°-80° C.), filtered and allowed to cool to room temperature (≈25° C.) to yield 2-isopropyl-7-methyl-8-nitro-1,2,3,3a,4,5-hexahydroimidazo-[1,5-a]-quinoline (1.25 g.) in the form of red clusters, m.p. 83°-84° C.

Anal.

Calcd. for $C_{15}H_{21}N_3O_2$: C, 65.46; H, 7.64; N, 15.27.

Found: C, 65.30; H, 7.56; N, 14.96.

EXAMPLE II

A solution of acetaldehyde (2.5 ml.) in absolute ethanol (10 ml.) was added to a solution of 2-isopropylaminomethyl-6-methyl-7-nitro-1,2,3,4-tetrahydroquinoline (1.0 g.) in absolute ethanol (30 ml.). The slightly exothermic reaction mixture was then allowed to stand at room temperature (25° C.) for 2 hours, after which time the solution was concentrated in vacuo. The resulting orange oil was dissolved in hot petroleum ether (b.p. 60°-80° C.) and thereafter allowed to cool to afford 1,7-dimethyl-2-isopropyl-8-nitro-1,2,3,3a,4,5-hexahydroimidazo-[1,5-a]-quinoline (0.75 g.) as an orange fluffy solid, m.p. 103°-104° C.

Anal.

Calcd. for $C_{16}H_{23}N_3O_2$: C, 66.43; H, 7.96; N, 14.53.

Found: C, 66.23; H, 7.81; N, 14.29.

EXAMPLE III

Formalin (20 ml.) was added to a solution of 6-hydroxymethyl-2-isopropyl-aminomethyl-7-nitro-1,2,3,4-tetrahydroquinoline (2.0 g.) in ethanol (125 ml.) and the resulting reaction mixture was set aside at room temperature (≈25° C.) for a period of four hours. The solvents were then removed from the solution in vacuo, and the crude product obtained in this manner was subsequently treated with dilute

aqueous sodium hydroxide (5N) and then extracted with chloroform (2 x 75 ml.). The chloroform solution was dried over anhydrous magnesium sulfate and concentrated in vacuo to afford 2-isopropyl-7-hydroxymethyl-8-nitro-1,2,3,3a,4,5-hexahydroimidazo-[1,5-a]-quinoline, which recrystallized from methanol as a golden yellow fluffy solid (1.85 g.), m.p. 159°-160° C.

Anal.

Calcd. for $C_{18}H_{21}N_3O_3$: C, 61.86; H, 7.22; N, 14.43.
Found: C, 62.00; H, 7.01; N, 14.10.

EXAMPLE IV

Propionaldehyde (5 ml.) was added to a solution of 2-isopropylaminomethyl-6-methyl-7-nitro-1,2,3,4-tetrahydroquinoline (1.6 g.) in ethanol (50 ml.). After about 15 minutes, an orange solid precipitated and the reaction mixture was then allowed to stand at room temperature (≈25° C.) for a further 2 hours. The mixture was then filtered, and the orange fluffy solid washed with ethanol and dried in vacuo to yield 1.4 g. of 1-ethyl-2-isopropyl-7-methyl-8-nitro-1,2,3,3a,4,5-hexahydroimidazo-[1,5-a]-quinoline, m.p. 122°-124° C.

Anal.

Calcd. for $C_{17}H_{25}N_3O_2$: C, 67.33; H, 8.25; N, 13.85.
Found: C, 67.26; H, 8.12; N, 13.75.

EXAMPLE V

30 A large excess of benzaldehyde (7.1 g.) was added to a well-stirred solution of 2-isopropylaminomethyl-6-methyl-7-nitro-1,2,3,4-tetrahydroquinoline (1.5 g.) in absolute ethanol (20 ml.) which was warmed to about 50° C. via a water-bath. After stirring for a period of 4 hours, a further quantity of benzaldehyde (10 ml.) was added to the mixture and the resulting reaction solution was maintained at this point (i.e., 50° C.) for a further 3 hours. The alcohol was then removed by means of evaporation under reduced pressure, and the crude product so obtained was subsequently dissolved in benzene and chromatographed on a neutral alumina column, using benzene as the eluent. The first 25 ml. of eluent was shown by thin-layer paper chromatographic analysis to contain benzaldehyde and a compound which was not the original starting material. The 35 benzaldehyde was removed (and recovered) by distillation in vacuo (b.p. 65°C./18 mm. Hg.) and the residue dissolved in hot petroleum ether (b.p. 60°-80° C.). On cooling to room temperature, the solution soon deposited 1-phenyl-2-isopropyl-7-methyl-8-nitro-1,2,3,3a,4,5-hexahydroimidazo-[1,5-a]-quinoline (850 mg.) as orange crystals, m.p. 130°-131 °C.

Anal.

Calcd. for $C_{21}H_{25}N_3O_2$: C, 71.77; H, 7.17; N, 11.96.
55 Found: C, 71.71; H, 7.06; N, 12.19.

EXAMPLE VI

A mixture of formalin (10 ml.) and 7-chloro-6,8-dimethyl-2-isopropylaminomethyl-1,2,3,4-tetrahydroquinoline (1.05 g.) 60 in ethanol (30 ml.) was shaken for a period of one hour. The reaction mixture was then poured into water and the resulting white solid extracted into diethyl ether. The ethereal solution was dried over anhydrous magnesium sulfate and subsequently evaporated in vacuo to yield a colorless oil, which was then dissolved in ethyl acetate and treated with a solution of one equivalent of maleic acid in hot ethyl acetate. Upon the addition of dry diethyl ether to the combined ethyl acetate solution, there were ultimately obtained 1.2 g. of 2-isopropyl-7,9-dimethyl-8-chloro-1,2,3,3a,4,5-hexahydroimidazo-[1,5-a]-quinoline hydrogen maleate as a white powder, m.p. 133° C.

Anal.

Calcd. for $C_{16}H_{23}ClN_2C_4H_4O_4$: C, 60.80; H, 6.89; N, 7.09.
75 Found: C, 60.83; H, 6.74; N, 6.53.

EXAMPLE VII

Acetaldehyde and 2-methylaminomethyl-6-methyl-7-nitro-1,2,3,4-tetrahydroquinoline were reacted exactly as described in Example II for the corresponding 2-isopropylaminomethyl compound. In this particular case, the product obtained was recrystallized from petroleum ether (b.p. 60°-80° C.) to afford pure 1,2,7-trimethyl-8-nitro-1,2,3,3a,4,5-hexahydroimidazo-[1,5-a]quinoline as an orange powder, m.p. 100°-102° C.

Anal.

Calcd. for $C_{14}H_{19}N_3O_2$: C, 64.37; H, 7.28; N, 16.10.
Found: C, 64.77; H, 7.16; N, 15.99.

EXAMPLE VIII

Thiophene-2-aldehyde and 2-isopropylaminomethyl-6-methyl-7-nitro-1,2,3,4-tetrahydroquinoline were reacted in ethanol in the manner described in Example II for acetaldehyde, except that the reaction-time period was extended to 17 hours. The red oil obtained on evaporation of the alcohol was crystallized from petroleum ether (b.p. 60°-80° C.) and then twice recrystallized from n-hexane to yield 1-(2-thienyl)-2-isopropyl-7-methyl-8-nitro-1,2,3,3a,4,5-hexahydroimidazo-[1,5-a]quinoline as a yellow fluffy solid, m.p. 134°-135° C.

Anal.

Calcd. for $C_{19}H_{23}N_3O_2S$: C, 63.86; H, 6.44; N, 11.76.
Found: C, 63.94; H, 6.59; N, 11.74.

EXAMPLE IX

o-Nitrobenzaldehyde was reacted with 2-isopropylaminomethyl-6-methyl-7-nitro-1,2,3,4-tetrahydroquinoline in the same manner as described in Example V for benzaldehyde, except that the reaction mixture

was refluxed on a steam bath in order to ensure completeness. After chromatographing in the usual manner to eliminate impurities, 1-(2-nitrophenyl)-2-isopropyl-7-methyl-8-nitro-1,2,3,3a,4,5-hexahydroimidazo-[1,5-a]quinoline was obtained, m.p. 95°-97° C.

Anal.

Calcd. for $C_{22}H_{24}N_4O_4$: C, 63.63; H, 6.06; N, 14.14.
Found: C, 63.37; H, 6.19; N, 14.32.

EXAMPLE X

A solution of 6-ethoxymethyl-2-isopropylaminomethyl-7-nitro-1,2,3,4-tetrahydroquinoline (2.5 g.) in ethanol (90 ml.) was treated with an alcoholic solution of acetaldehyde (7.5 ml.) in ethanol (30 ml.). A mildly exothermic reaction then ensued and after 1 hour, thin-layer paper chromatographic analysis indicated that the reaction was essentially complete. The reaction solution was then evaporated to dryness while under reduced pressure to give 1-methyl-2-isopropyl-7-ethoxymethyl-8-nitro-1,2,3,3a,4,5-hexahydroimidazo-[1,5-a]quinoline as an orange solid, which was subsequently recrystallized from ethanol to yield 1.6 g. of product, m.p. 103°-105° C.

Anal.

Calcd. for $C_{18}H_{27}N_3O_3$: C, 64.85; H, 8.11; N, 12.62.
Found: C, 64.45; H, 8.39; N, 12.62

EXAMPLE XI

The following substituted hexahydro imidazoquinoline compounds are prepared by employing the condensation procedure described in the previous examples, starting from the corresponding 2-aminomethyl-1,2,3,4-tetrahydroquinoline base and the appropriate aldehyde (R_6-CHO) reagent of choice in each instance:

EXAMPLE XII

A mixture of 2.0 g. of 2-isopropyl-7-methyl-8-nitro-1,2,3,3a,4,5-hexahydroimidazo-[1,5-a]-quinoline and a three molar excess of 30 percent hydrogen peroxide in 15 ml. of acetone is stirred at room temperature ($\approx 25^\circ \text{C}$) for a period of 3 days. An additional quantity of 30 percent hydrogen peroxide (a five molar excess) is then added and the stirring thereafter continued for a further seven hours. At this point, the reaction is substantially complete and the excess hydrogen peroxide is decomposed by the addition of platinum oxide to the spent mixture. Upon filtering and removal of the solvent by concentration in vacuo, there is obtained a viscous oil as the liquid residue. Trituration of the latter material with diethyl ether then gives a powdery solid, which is subsequently collected by means of filtration and recrystallized from acetone to afford pure 2-isopropyl-7-methyl-8-nitro-1,2,3,3a,4,5-hexahydroimidazo-[1,5-a]-quinoline N-oxide as a crystalline solid.

In like manner, the other N-oxide compounds of this invention are each similarly formed by merely employing the appropriate substituted 1,2,3,3a,4,5-hexahydroimidazo-[1,5-a]-quinoline base as starting material in the above reaction procedure, in place of the particular quinoline base compound used previously.

What is claimed is:

1. A hexahydro imidazoquinoline compound selected from the group consisting of substituted 1,2,3,3a,4,5-hexahydroimidazo-[1,5-a]-quinoline bases of the formula:

and the N-oxide derivatives and pharmaceutically acceptable acid addition salts thereof, wherein R₁ is alkyl having from one to six carbon atoms; R₂ is a member selected from the group consisting of methyl and hydroxymethyl; R₃ is a member selected from the group consisting of nitro and chlorine; R₄ is hydrogen; R₅ is a member selected from the group consisting of hydrogen and methyl; and R₆ is a member selected from the group consisting of hydrogen, alkyl having from one to six carbon atoms, phenyl, nitrophenyl and thiienyl.

5 10 2. A compound as claimed in claim 1 wherein R₁ is alkyl having from one to six carbon atoms, R₂ is methyl, R₃ is nitro, and R₄, R₅ and R₆ are each hydrogen.

15 3. A compound as claimed in claim 1 wherein R₁ is alkyl having from one to six carbon atoms, R₂ and R₅ are each methyl, R₃ is chlorine, and R₄ and R₆ are each hydrogen.

20 4. A compound as claimed in claim 1 wherein R₁ is alkyl having from one to six carbon atoms, R₂ is hydroxymethyl, R₃ is nitro, and R₄, R₅ and R₆ are each hydrogen.

5 25 5. A compound as claimed in claim 1 wherein R₁ and R₆ are each alkyl having from one to six carbon atoms, R₂ is methyl, R₃ is nitro, and R₄ and R₅ are each hydrogen.

30 6. A compound as claimed in claim 1 wherein R₁ is alkyl having from one to six carbon atoms, R₂ is methyl, R₃ is nitro, R₄ and R₅ are each hydrogen, and R₆ is phenyl.

7. A compound as claimed in claim 1 wherein R₁ is alkyl having from one to six carbon atoms, R₂ is methyl, R₃ is nitro, R₄ and R₅ are each hydrogen, and R₆ is nitrophenyl.

35 8. A compound as claimed in claim 1 wherein R₁ is alkyl having from one to six carbon atoms, R₂ is methyl, R₃ is nitro, R₄ and R₅ are each hydrogen and R₆ is thiienyl.

9. The compound as claimed in claim 3 wherein R₁ is isopropyl and R₅ is methyl.

10. The compound as in claim 4 wherein R₁ is isopropyl.
